NAIL CLIPPER

Paul H. Smith, Brockton, Mass.

Application March 21, 1938, Serial No. 197,315

4 Claims. (Cl. 30—28)

This invention relates to manicuring implements and has reference in particular to what is believed to be a new style fingernail clipper, that is, one embodying a depository for convenient accumulation and trapping of the clippings.

This application is a continuation in part of an application filed by me on August 26, 1937, Serial No. 161,167.

There are certain known fingernail clippers characterized by a complementary spring separated and lever actuated clipping or cutting element. The present invention is characterized by a somewhat corresponding coordination of parts but has associated therewith unique cam coacting pressure means as well as an appropriately arranged and aptly designed receptacle constituting the depository.

More specifically stated, I have evolved and produced a nail clipper of the aforementioned general type embodying a main channel shaped member forming the receptacle, a resilient cover member cooperable therewith, and a special adaptation of slotted flanges to accommodate the fulcruming and cam elements on the operating lever.

Other features and advantages will become more readily apparent from the following description and the accompanying illustrative drawings.

In the drawings, wherein like numerals are employed to designate corresponding mechanical details throughout the views:

Figure 1 is a top plan view of the novel nail clipper as constructed in accordance with the structural principles of the present invention.

Figure 2 is a central longitudinal sectional view taken approximately on the plane of the line 2—2 of Figure 1.

Figure 3 is a view similar to Figure 2 showing how the cam coacting means comes into play to provide the necessary leverage to operate the resilient clipping member.

Figure 4 is a top plan view exposing the receptacle, the resilient cover plate or companion part thereof being broken away for clearance of illustration.

Figure 5 is a side view of that portion of the construction seen in Figure 4.

Figure 6 is a top plan view of the so-called resilient cover plate.

Figure 7 is a top plan view of the operating lever.

Figure 8 is an edge view of the same.

Referring now to the drawings by distinguishing reference numerals, it will be observed that

the numeral 9 designates the clipper unit, this part being of metal of proper texture and composition strength. The channel shaped portion includes spaced parallel side walls 10 and an intervening web 11, the web being longitudinally shaped to cooperate with the side walls in providing a depository for the nail clippings. The outer or left-hand end of this part 11 is formulated into the usual arcuate or segmental nipper or cutter 12. The side walls 10 adjacent to the cutter 12 are provided with extensions which may be conveniently called adapter flanges 13. These flanges are provided with duplicate horizontally elongated slots 14 to accommodate the retention and fulcruming lugs 15 on the operating lever 16. It will be observed in Figure 5 in particular, that the upper edges of the respective slots are provided with selectively usable notches or seats 17 and 18. That section of the unit 9 identified by numeral 19 forms the aforementioned cover plate and is of a length corresponding to the receptacle and is integrally connected at one end as at 20 to the corresponding end of the receptacle. The construction at 20 is such as to provide the desired spring hinge connection, the resiliency being such as to normally press or swing the part 19 away from the receptacle. Thus the part 19 becomes a relatively movable cutter and it is provided on its outer end with a nipper 21 corresponding to the aforementioned nipper 12. At the point 22 the movable cutter 19 is provided with an aperture which constitutes a convenient means for dumping the deposited clippings whenever necessary or desired. It will be further noted that this part 19 is provided with a somewhat pyramidal riser or button 23. This constitutes a depressing or thrust element and is located for coaction with the slot 14 and companion portion of the lever 16.

In connection with the lever it will be observed that the extreme outer end is directed laterally as at 24 in respect to the retention and pivoting lugs 15. Then on the opposite side of the lugs said lever is fashioned as at 25 to provide a thrust rib or cam for cooperation with the complementary cam or thrust element 23.

Under this arrangement the lever may be shifted to its "off" and "on" positions. For example, in Figure 2 we see the lever in its collapsed or folded position to facilitate carrying the device in one's pocket. At this time the lugs 15 engage in the seats 18 and the detent 24 rests upon the button 23. The inherent resiliency of the spring cover plate 19 exerts pressure on the detent whereby to maintain the lever in this out-of-the-

way collapsed position. This, incidentally, is one outstanding feature of the invention.

It is also observable that by shifting the lugs from the seats 18 into the outer or front seats 17, the lever may be swung to an open operable position for depressing the spring plate 19. When in the latter position, as illustrated in Figure 3, the cam element or rib 25 comes into engagement with the thrust button 23 to provide the desired pressure for actuating the nippers 12 and 21 in a well-known manner. In order to move the lever 16 from its rear position shown in Figure 2 to its forward position said lever 16 is slightly raised so as to slightly depress the member 19 and then the lever is moved forwardly so as to move the trunnions 15 from out of the seats 18 into the seats 17.

The disclosure of the invention thus made comprehends the preferred embodiment of the inventive concept. I desire to emphasize, however, in a construction of this major it is desirable of visualizing the features separately and collectively to appreciate their companion coordination, each sharing its proportionate part in the contribution to a unitary implement possessed of the advantages indicated.

It is thought that the description taken in connection with the drawings will enable a clear understanding of the invention to be had. Therefore, a more lengthy description is thought unnecessary.

While the preferred embodiment of the invention has been shown and described, it is to be understood that minor changes coming within the field of invention claimed may be resorted to if desired.

I claim:

1. In a nail clipper of the class described, a stationary jaw provided with a nipper, a relatively movable resiliently operable companion jaw having a nipper opposed to said first named nipper, the stationary jaw being provided with spaced parallel flanges having elongated slots, said slots having selectively usable keeper seats formed therein, a lever having lugs slideable in said slots and selectively disposable in said seats, said lever having a cam member for coaction with the adjacent jaw as well as a detent, said detent constituting means for maintaining the lever in compact folded relation.

2. A nail clipper of the class described comprising a relatively stationary jaw having a cutter at one end, a relatively movable jaw having integral resilient hinging connection with said first named jaw and provided with a nipper opposed

to said first named nipper, said first named jaw being provided with spaced parallel flanges having longitudinally elongated slots therein, said slots being provided with selectively usable keeper notches, a lever having lugs, slideable in said slots and selectively disposable in said seats, said lever being positioned between said flanges and said lugs being slidably mounted in said slots, said movable jaw being provided with a thrust member, said lever having a cam member for cooperation with said thrust member and being further provided with a detent for selected cooperation with said thrust member.

3. A nail clipper of the class described comprising a longitudinally elongated channel shaped member forming a depository, the outer end wall of said depository being provided with a nail nipper, the side walls of said channel shaped member having slotted flanges, a cover plate of a length corresponding to said channel shaped member having hinge connection at one end with said channel shaped member, the outer end of said cover plate being provided with a nipper opposed to said first named nipper, and an intermediate part of the cover plate having an aperture therein for discharge of clippings, and being further provided inwardly of said nipper with an upstanding riser forming a thrust element, and a lever slidably fulcrumed between said flanges and having cam means cooperable with said thrust member when the lever is in one position and said lever having a detent for engaging the thrust member when the lever is in a second position, said detent maintaining the lever in position against the cover plate.

4. In a nail clipper of the class described, an elongated channel-shaped member having elongated longitudinally extending slots in its side walls adjacent the front end thereof and the bottom wall having a nipper at its front end, a cover plate hingedly connected at its rear end to the rear end of the bottom wall of the channel-shaped member and having a nipper at its front end, a lever having trunnions extending from its side edges adjacent the front end thereof for engaging the slots, said lever when moved upwardly having a part engaging the front end of the cover plate for moving the cover plate downwardly to force the nippers into cutting relationship, when the lever is in one position with respect to the slots and coacting parts between the cover plate and the lever for holding the cover plate in lowered position and the lever resting on the cover plate when the lever is in a second position.
